UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MECHANISM FOR ASSEMBLING MATCH STRIPS.

Application filed January 26, 1927. Serial No. 163,608.

This invention relates to mechanism for assembling match strips, having reference more especially to mechanism for intercepting strips of matches as they are discharged 5 from a match making machine and arranging them in an orderly manner, with the strips alternately reversed as respects the heads of the matches, which strips are intended to be subdivided into sections of 10 proper size for use in the manufacture of match books.

In the preferred embodiment of my invention herein illustrated the match strips are ejected in succeeding pairs from a match 15 making machine and the paired strips are alternately reversed and assembled in such manner as to facilitate their introduction in a suitable holder for subsequent transference to the match-strip supply magazine, 20 for example, of a machine for making match-books.

My invention, generally stated, comprises transfer mechanism, including a succession 25 of holders which receive the successive match strips, or pairs of strips, as they are removed from the source of match supply and deliver them with the alternate strips or pairs of strips reversed as respects their heads; means for ensuring the orderly arrangement 30 of the match strips in the said holders; means for uniformly ejecting the match strips from the successive holders; and take-off means for receiving the ejected match strips and supporting them in assembled relation.

The invention also comprises novel features of construction and combinations of parts, all of which will be hereinafter described, and the scope of the invention then 40 be defined in the appended claims.

In the drawings—

Figure 1 is a front elevation, partly in section, of match-strip assembling mechanism embodying a preferred form of my invention, showing its relation to the discharge station of a match making machine.

Fig. 2 is a transverse vertical section of said mechanism, as on the line 2—2 of Fig. 1.

Fig. 3 is a longitudinal vertical section, partly in elevation, of the same.

Fig. 4 is a transverse vertical section, as on the line 4—4 of Fig. 3.

Fig. 5 is a partial horizontal section, as on the line 5—5 of Fig. 4.

Fig. 6 is a skeleton perspective illustrating the take-off mechanism and adjuncts. 55

Fig. 7 is a perspective of one of the rotatable match-strip holders.

Referring to the drawings, 10 designates a portion of the travelling endless carrier 60 of a machine for making match strips; and 11 the punch head for ejecting the depending match strips 12 in successive pairs from the carrier at the discharge station of the machine. At this station the longitudinal side links 13 of the carrier are guided in parallel trackways 14 on the supporting frame structure 15, which links are formed, as usual, with rack teeth in mesh with gear wheels 16 fast on a continuously driven 65 transverse shaft 17 having its bearings in brackets 18 located at the respective sides of the frame structure.

Directly below the discharging station of the match machine is strip receiving and positioning mechanism, including in its construction a succession of travelling holders 19, 20 which intercept the successive pairs of ejected match strips at regular intervals apart and transfer them thence to a point 75 where the paired strips are successively ejected in a substantially vertical plane from the holders and deposited in upright position upon suitable underlying assembling 80 and take-off mechanism hereinafter described. The alternate holders, 20, are independently turned through an arc of 180° 85 in a period of their travel between the receiving and the ejecting point, thereby reversing the positions of the heads of the 90 strips contained in said holders, 20, in relation to the heads of the strips in the adjacent holders 19.

The strip receiving and positioning mechanism herein illustrated is of the following 95 construction: 24 designates two spaced-apart cylindrical sections headed at their outer ends. Through these sections centrally extends a transverse shaft 25 which is journaled in suitable bearings 26 projecting from the heads 27 of the respective sections, which bearings are bolted to the main supporting frame of the machine. On one end of the shaft 25 is fixed a gear 28 in mesh with a gear 29 on the shaft 17, whereby during the 100 105

rotation of the latter shaft motion is transmitted to the shaft 25.

The sections 24 are arranged with their upper portions in proximity to the path of the heads of the match strips depending from the carrier, the inner edges of such portions being cut-away, as at 30, to permit the free passage of the pendant match strips above the sections, and also to permit the strips, when they are ejected from the carrier, to enter the space between the open ends of the sections.

Fast on the shaft 25 are the hubs of spaced-apart duplicate turrets 31 which are located in the respective casing sections 24 and are concurrently rotatable therein by actuation of the shaft. The inner face of each of the turrets 31 has formed thereon, adjacent its periphery, a series of segmental projections 32, which are so formed and spaced apart as to afford a series of radial slots constituting the holders 19, and also to present a series of substantially circular recesses 33, which slots and recesses are open at the inner and outer peripheral edges of the projections and are arranged in alternation and in equally spaced relation. The corresponding slots and recesses of the respective turrets are in horizontal alignment with each other, and they are so diametrically disposed that when, in the rotation of the turrets, a pair of complementary slots or recesses are positioned at the top of the casing sections two adjacent match strips are ejected from the carrier by the punch head 11.

Rotatable in each of the recesses 33 are a pair of spaced-apart oppositely curved wings 34 constituting an open holder 20, flared at its respective ends, which wings project from a head 35 formed on or secured to one end of a central stud 36 journaled in a bearing 37 at the peripheral portion of the turret. Fast on the opposite end of the stud 36 is a pinion 38 having a boss or hub 39 formed with oppositely-disposed arcuate recesses 40 which co-operate alternately with the peripheral portion 41 of a stationary annular plate 42, in a manner to lock the head 35, with one end of its holders in vertical position, when the holder is located at the top of the turret, and to lock the holder in an inverted position when it is located at the bottom of the turret. The periphery of the plate 42, which is fastened to the adjacent end head 27, is interrupted by an arcuate offset portion 43 in the path of travel of the hub 39 from the upper to the lower level, and hence when such hub reaches and traverses this offset portion, the holder 20, is unlocked and consequently may be independently rotated on its axis.

Stationary sectors 44 underlie the respective holders 19, 20 located at the top of the turrets and extend thence to a point adjacent the supplemental holders which are posi-

tioned at the bottom of the turrets, said sectors, in conjunction with the adjacent cylindrical walls of the sections 24, thus maintaining the match strips seated within the respective holders until the strips have been advanced by the turrets from the upper receiving to the lower discharging level. The casing sections 24 are suitably recessed at 45 to permit the descent of the match strips therefrom at the lower level.

The sectors 44 have hubs 46 which are fixedly secured to spaced-apart split hubs 47 freely encircling the shaft 25, which latter hubs are fast on a pair of horizontal bars 48 that extend outwardly beyond the casing sections 24 and are fixedly secured, as at 49, to the inner peripheral edges of the respective sections. In the present instance, the ratio of the co-acting gears 29, 28 on the shafts 17 and 25 is such that the peripheral speed of the turrets 31 slightly exceeds the surface speed of the carrier 10, and therefore the punch-head 11 is timed to start the discharge of the strips from the carrier into each succeeding holder (19 or 20) before the holder reaches its upper central position, which holder passes such position before the strips are fully discharged into the holder.

The preferred means for actuating the rotatable holders 20 is as follows: Fast on the inner face of the plate 42 is a gear segment 50 with which meshes the pinion 38 of each rotary holder 20 during the unlocked interval of travel of the latter, said pinion, together with the holder, thus being independently turned on its axis. The ratio of the pinion and segment is such that the holder 20 is rotated through an arc of 180°, thus reversing the contained match strips with respect to the strips contained in the adjacent holders 19. When the pinion escapes the gear segment the inner arcuate recess 40 of the hub 39 engages the locking periphery of the plate 42 and remains in engagement therewith until the hub again reaches the offset portion 43 of the plate and the pinion re-engages the gear segment; and so on.

As the match strips contained in the successive holders reach the lowermost or discharging position, the strips are positively ejected from the holders. Preferably the strip ejecting means comprises a series of beater arms 51 which are mounted to rotate within the space between the lower portions of the casing sections in a manner successively to strike the tops of the opposing match strips. These arms project from a sleeve 52 loosely mounted on a stud-shaft 53 supported by a bracket 54 in one of the casing sections, which sleeve has a gear 55 thereon in mesh with a gear 56 fast on the inner end of a lower horizontal shaft 57 extending to one side of the machine. The shaft 57, which has its bearings in suitably-disposed brackets 58, is equipped at its outer end with a pinion

59 in mesh with the gear 28 on the shaft 25, and hence during the rotation of the gear 28 rotary motion is transmitted to the sleeve and is arm 51.

5 In order to maintain each pair of match strips in close lateral relation when they are presented to the action of the beater arms, thus insuring their uniform ejection from the holder, I preferably pivot, as at 60, to 10 the webs of the respective sectors 44 a pair of pendant gravity arms 61, the free ends of which are weighted, as at 62, and arranged in the path of the strips as the latter approach the point of discharge from the 15 holders. The progressing paired strips bear against the opposing weighted ends of the arms 61 and the latter press the strips together and yield therewith until the strips have been ejected by the beaters, whereupon 20 the arms swing backward into the path of the next succeeding pair of strips, and so on.

As a simple and efficient means to straighten any irregularly disposed match strips in the respective holders 19, 20, I provide a vibratory evener which is arranged to press upon the outer longitudinal edges (margins or heads) of the paired strips during their initial traverse in the holders. This evener, in the form illustrated, comprises a pair of 30 spaced-apart upwardly-inclined plates 63 mounted to swing within the outer portion of the space between the casing sections and somewhat rearward of the receiving position of the strip holders. The plates are 35 fast on a rock-shaft 64 having its bearings in lugs 65 on the respective casing sections. One end of the shaft 64 extends outwardly and is provided with a depending crank arm 66 which is connected by means of a link 67 40 with an eccentric wrist pin 68 on a pinion 69 fast on a lower shaft 70 having its bearing in a bracket 71 on the adjacent casing section. The pinion 69 meshes with a gear 72 on the shaft 57, and hence during the 45 rotation of such gear the pinion 69 is rotated, thus effecting, through the described link and crank connection, the rapid vibration of the evener plates 63 in respect to the opposing match strips.

50 The assembling and take-off mechanism preferably comprises a pair of spaced-apart belts 21 underlying the turrets and passing about suitably-disposed pulleys, one pair of which are mounted on a shaft 22 continuously driven from a suitable source. The upper horizontal runs of the belts are supported on parallel bars 23, and are arranged to receive and advance the vertically-disposed strips discharged from the succeeding 55 holders. Upstanding side plates 21' are secured to the respective bars in the vicinity of the delivery station so as to support and guide the match strips in upright position, a weight 22' loosely imposed on the belt and 60 movable between the side plates serving as

a back stop for the strips, which stop contacts with yielding stops 23' on the inner side of one of the plates to hold the match strips in upright position. The stops 23' are preferably composed of thin strips of spring 70 metal let into a groove in the inner side of the adjacent plate and each attached at its forward end to the plate, so that there will be no liability of the opposing ends of the strips, as they are advanced, catching on 75 the fixed ends of the springs. (See Figs. 4 and 6.)

In order positively to advance the strips between the side plates, as rapidly as they are positioned on the belts, and ensure the close relation of the assembled strips, I provide a horizontally-reciprocatative pusher 73 which extends transversely of the belts and acts uniformly against the opposing strips. In the present instance, this pusher comprises an angular bar fast on a carriage comprising a body 74 having flanged wheels 75 mounted to run on parallel rails 76 supported between the belts. The body 74 is formed on an arm 77 pivoted, as at 78, to the lower end of a depending rock-arm 79, which arm, in turn, is pivoted to and between the stationary bars 48, hereinbefore referred to. (See Fig. 6.) On the rock-arm is a laterally projecting stud 80 having a crank-arm 81 which is pivoted to an eccentric pin 82 on a head 83 at the inner end of the shaft 70, whereby during the rotation of said shaft the rock-arm is actuated in a manner to effect the horizontal reciprocation of the carriage and the pusher in 90 timed relation to the operation of the beater arms.

It is to be understood that my invention is not limited to the particular construction or mechanism herein disclosed, as the same may be modified within the principle of the invention and the scope of the appended claims.

I claim—

1. The combination with means for supplying match strips, of a movable structure mounted adjacent thereto including a succession of relatively-fixed and independently-movable strip holders arranged in alternation, means for actuating said structure to locate the holders thereof successively in strip receiving position and advance them to a remote delivery location where the strips are discharged in a substantially vertical plane, means for independently moving the alternate holders to effect the reversal of the headed ends of their contained strips during the travel of the holders toward the delivery location, and a take-off element underlying the delivery location and adapted to receive the successively discharged strips and support them in assembled relation.

2. The combination with means for supplying match strips, of a movable structure

- mounted adjacent thereto including a succession of relatively fixed and independently rotatable strip holders arranged in alternation, means for actuating said structure to locate the holders thereof successively in strip receiving position and advance them to a remote delivery location where the strips are discharged in a substantially vertical plane, means for independently moving the alternate holders to effect the reversal of the headed ends of their contained strips during the travel of the holders toward the delivery location, and a take-off element including a travelling conveyor underlying the delivery location and adapted to receive the successively discharged strips and support them in assembled relation.

3. The combination with means for supplying match strips, of a turret structure mounted adjacent thereto including a succession of relatively fixed strip holders, a series of independently rotatable holders alternating with said fixed holders, means for rotating said turret structure to locate the said holders successively in strip receiving position and advance them to the delivery location where the strips are discharged in a substantially vertical plane, means for independently actuating the rotatable holders to effect the reversal of the headed ends of the strips contained in the latter holders during their travel toward the delivery location, and a take-off element underlying the delivery location and adapted to receive the successively discharged strips and support them in assembled relation.

4. The combination with means for supplying match strips, of a turret structure mounted adjacent thereto including a succession of relatively fixed strip holders, a series of independently rotatable strip holders alternating with said fixed holders, means for rotating said turret structure to locate the said holders successively in strip receiving position and advance them to a remote delivery location where the strips are discharged in a substantially vertical plane, means for independently actuating the rotatable holders to effect the reversal of the headed ends of the strips contained in the latter holders during their travel toward the delivery location, and a take-off element including a travelling conveyor underlying the delivery location and adapted to receive the successively discharged strips and support them in assembled relation.

5. The combination with means for supplying match strips, of a turret structure mounted adjacent thereto including a succession of relatively fixed strip holders, a series of independently rotatable holders alternating with said fixed holders, means for rotating said turret structure to locate the said holders successively in strip receiving position and advance them to a remote de-

livery location where the strips are discharged in a substantially vertical plane, gearing for independently actuating the rotatable holders to effect the reversal of the headed ends of the strips contained in the latter holders during their travel toward the delivery location, means for temporarily locking the rotatable holders in their respective positions, and a take-off element underlying the delivery location and adapted to receive the successively discharged strips and support them in assembled relation.

6. The combination with means for supplying match strips, of a turret structure mounted adjacent thereto including a succession of relatively fixed strip holders, a series of independently rotatable holders alternating with said fixed holders, means for rotating said turret structure to locate the said holders successively in strip receiving position and advance them to a remote delivery location where the strips are discharged in a substantially vertical plane, gearing for independently actuating the rotatable holders to effect the reversal of the headed ends of the strips contained in the latter holders during their travel toward the delivery location, means for temporarily locking the rotatable holders in their respective positions, and a take-off element including a traveling conveyor underlying the delivery location and adapted to receive the successively discharged strips and support them in assembled relation.

7. The combination with means for supplying match strips, of a movable structure mounted adjacent thereto including a succession of relatively-fixed and independently movable strip receiving holders arranged in alternation, means for actuating said structure to locate the holders thereof successively in strip receiving position and advance them to a remote delivery location where the strips are discharged in a substantially vertical plane, means for independently moving the alternate holders to effect the reversal of the headed ends of their contained strips during the travel of the holders toward the delivery location, yielding means at the said location for retaining the strips in each succeeding holder, means for forcibly ejecting the strips from the holders, and a supporting and assembling element for the ejected strips.

8. The combination with means for supplying match strips, of a movable structure mounted adjacent thereto including a succession of relatively-fixed and independently movable strip receiving holders arranged in alternation, means for actuating said structure to locate the holders thereof successively in strip receiving position and advance them to a remote delivery location where the strips are discharged in a substantially vertical plane, means for independently moving the

alternate holders to effect the reversal of the headed ends of their contained strips during the travel of the holders toward the said delivery location, yielding means at the 5 said location for retaining the strips in each succeeding holder, said yielding means comprising a pendant gravity member extending into the path of the strips, means for ejecting the strips from the holders, and a supporting and assembling element for the ejected strips.

9. The combination with means for supplying match strips, of a movable structure mounted adjacent thereto including a succession of relatively-fixed and independently movable strip receiving holders arranged in alternation, means for actuating said structure to locate the holders thereof successively in strip receiving position and advance them to a remote delivery location where the strips are discharged in a substantially vertical plane, means for independently moving the alternate holders to effect the reversal of the headed ends of their contained strips during the travel of the holders toward the delivery location, yielding means at the said location for retaining the strips in each succeeding holder, rotatable beater members for ejecting the strips from the successive holders, means for rotating said members, and a supporting and assembling element for the strips ejected from the holders.

10. The combination with means for supplying match strips, of a movable structure mounted adjacent thereto including a succession of relatively-fixed and independently-movable strip holders arranged in alternation, means for actuating said structure to locate the holders thereof successively in strip receiving position and advance them to a remote delivery location where the strips are discharged in a substantially vertical plane, means for straightening the strips in the successive holders, means for independently moving the alternate holders to effect the reversal of the headed ends of their contained strips during the travel of the holders toward the delivery location, and a supporting and assembling element to which the strips are delivered by the holders.

11. The combination with means for supporting match strips, of a movable structure mounted adjacent thereto including a succession of relatively-fixed and independently-movable strip holders arranged in alternation, means for actuating said structure to locate the holders thereof successively in strip receiving position and advance them to a remote delivery location where the strips are discharged in a substantially vertical plane, means for straightening the strips in the successive holders, said straightening means comprising a vibratory member 65 which impinges against the outer portions of

the strips contained in the holders and means for actuating said member, means for independently moving the alternate holders to effect the reversal of the headed ends of their contained strips during the travel of the holders toward the said delivery location, and a supporting and assembling element to which the strips are delivered by the holders.

12. The combination with means for supplying match strips, of a movable structure mounted adjacent thereto including a succession of relatively-fixed and independently-rotatable strip receiving holders arranged in alternation, means for actuating said structure to locate the holders thereof successively in strip receiving position and advance them to a remote location where the strips are delivered in a substantially vertical plane, means for independently moving the alternate holders to effect the reversal of the headed ends of their contained strips during the travel of the holders toward the delivery location, and a supporting and assembling element to which the strips are delivered by the holders, said element comprising a travelling conveyor, spaced side walls, a movable back stop for the strips, a pusher overlying the conveyor and operative against the opposing strips deposited on the conveyor, and means for reciprocating said pusher.

13. The combination of a pair of spaced-apart casing sections having inlet and outlet portions for the entry and discharge of match strips, turrets mounted to rotate in said sections and having spaced-apart open radial slots constituting strip holders, independently-rotatable elements including open holders mounted on the turrets in alternation with the first-named holders, means for rotating said turrets to present the successive holders to the said inlet and outlet portions of the casing sections, stationary members for supporting the inner portions of the strips during their travel in the holders from the said inlet to the outlet portions, and means for independently actuating the alternate rotatable elements to effect the reversal of the headed ends of the strips contained in their holders during the travel of the latter toward the outlet portions.

14. The combination of a pair of spaced-apart casing sections having inlet and outlet portions for the entry and discharge of match strips, turrets mounted to rotate in said sections and having spaced-apart open radial slots constituting strip holders, independently rotatable elements including open holders mounted on the turrets in alternation with the first-named holders, means for rotating said turrets to present the successive holders to the said inlet and outlet portions of the casing sections, stationary members for supporting the inner portions of

the strips during their travel in the holders from the said inlet to the outlet portions, gearing for independently actuating the rotatable elements to effect the reversal of the headed ends of the strips contained in their holders during the travel of the latter toward the outlet portions, and means for temporarily locking the rotatable holders in their respective positions.

- 10 15. The combination of a pair of spaced-apart casing sections having inlet and outlet portions for the entry and discharge of match strips, turrets mounted to rotate in said sections and having spaced-apart open radial slots constituting strip holders, independently-rotatable elements including open holders mounted on the turrets in alternation with the first-named holders, means for rotating said turrets to present the successive holders to the said inlet and outlet portions of the casing sections, stationary members for supporting the inner portions of the strips during their travel in the holders from the said inlet to the outlet portions, means for independently actuating the alternate rotatable elements to effect the reversal of the headed ends of the strips contained in their holders during the travel of the latter toward the outlet portions, yielding means located between the casing sections and adjacent the outlet portions for

temporarily retaining the strips in each succeeding holder, and means for forcibly ejecting the strips from the holders.

16. The combination of a pair of spaced-apart casing sections having inlet and outlet portions for the entry and discharge of match strips, turrets mounted to rotate in said sections and having spaced-apart open radial slots constituting strip holders, independently-rotatable elements including open holders mounted on the turrets in alternation with the first-named holders, means for rotating said turrets to present the successive holders to the said inlet and outlet portions of the casing sections, stationary members for supporting the inner portions of the strips during their travel in the holders from the said inlet to the outlet portions, means operative between the casing sections and rearward of the inlet portions for straightening the strips in the successive holders, and means for independently actuating the alternate rotatable elements to effect the reversal of the headed ends of the strips contained in their holders during the travel of the latter toward the outlet portions.

Signed at Barberton, in the county of Summit and State of Ohio this 24th day of January A. D. 1927.

JOSEPH C. DONNELLY.
